US0D1061588S

(12) **United States Design Patent** (10) **Patent No.:** **US D1,061,588 S**
(45) **Date of Patent:** **** Feb. 11, 2025**

(54) **DISPLAY SCREEN OR PORTION THEREOF HAVING A GRAPHICAL USER INTERFACE**

7,606,758 B1 10/2009 Sooklal
7,801,798 B1 9/2010 Huemer et al.
7,860,774 B1 12/2010 Peterson et al.
